CLAIM

I claim the ornamental design for a kitchen tool, as shown and described.

DESCRIPTION

FIG. 1 is a front perspective view of the kitchen tool showing my new design in an open configuration.

FIG. 2 is a front perspective view thereof in a closed configuration.

FIG. 3 is rear perspective view of FIG. 1.

FIG. 4 is a rear perspective view of FIG. 2.

FIG. 5 is a left side view of FIG. 1.

FIG. 6 is a left side view of FIG. 2.

FIG. 7 is a right side view of FIG. 1.

FIG. 8 is a right side view of FIG. 2.

FIG. 9 is a bottom plan view of FIG. 1.

FIG. 10 is a bottom plan view of FIG. 2.

FIG. 11 is a top plan view of FIG. 1.

FIG. 12 is a top plan view of FIG. 2.

FIG. 13 is a front view of FIG. 1.

FIG. 14 is a front view of FIG. 2.

FIG. 15 is a rear view of FIG. 1; and,

FIG. 16 is a rear view of FIG. 2.
